MAURICE O'CONNELL, OF BOSTON, MASSACHUSETTS.

Letters Patent No. 80,085, dated July 21, 1868.

IMPROVEMENT IN APPARATUS FOR CHECKING HORSES ATTACHED TO VEHICLES.

The Schedule referred to in these Letters Patent and making part of the same.

TO ALL WHOM IT MAY CONCERN:

Be it known that I, MAURICE O'CONNELL, of the city of Boston, in the county of Suffolk, and Commonwealth of Massachusetts, watchmaker, have invented a new and improved Mode of Effectually Checking a Horse or Horses Attached to any and all Kinds of Wheeled Vehicles, and preventing their running away when left standing; and I do hereby declare that the following is a full and exact description thereof, reference being had to the accompanying drawings, and to the letters and figures of reference marked thereon:

The nature of my invention consists in converting the wheels of any vehicle into a means of utilizing the power developed by the horse in his efforts to move, and making it the means of checking him, viz:

A A represent a pair of wheels, to the hub of each one of which is firmly attached, on the inside, a wheel of any convenient diameter, made of any kind of tenacious metal, or of any other tenacious and durable material, and having its periphery graduated and cut into a number of equal parts, forming the teeth of the first power, or driving-wheels, Nos. 1 1.

The diagram under letter B, and composed of the several pieces, numbered, consecutively, from 2 to 7, inclusive, supplies all that remains necessary to put the invention into operation. Its use, and the relation of its several parts to each other, as well as its construction and operation, I will proceed to describe, so as to enable all parties skilled in mechanics, and interested in the matter, to use my invention.

No. 4 is a shaft made of any kind of metal, hard wood, or any durable material, of sufficient strength for the use to which it is applied, and of length to reach across the vehicle, from one to the other of the wheels 1 1, attached to the hubs. On each end of this shaft is firmly affixed a small wheel or pinion, 2 2, so proportioned in diameter to that of the wheels 1 1, as, when impelled by them, to rotate with greater velocity than they do; and in its teeth or leaves so fitted to the teeth of the wheels, being cut or graduated by the same tool or process used for forming the teeth of the wheels, that the operation of the wheel on the pinion is made to be free and certain. The shaft, prior to affixing the pinions on its ends, is put through the two pivot-holes of a yoke or brace, No. 5, made of wrought or cast iron, or any other metal, those holes being exactly the diameter of the shaft, and intended, in the yoke, to supply the bearings or pivot-holes for the shaft to rotate in. Between the arms of the yoke or brace 5 is introduced the small barrel, No. 3, so closely fitted in length to the space between the arms of the yoke, that it has barely end-chase or freedom enough to revolve. The diameter of the bore of this barrel is exactly that of the shaft, which, when passed through the arms of the yoke and the intermediate barrel, is, by a single pin through or across its centre, so firmly united with the barrel, that they become one, the ends of the barrel resting against the arms of the yoke, and acting as shoulders to the pivots, which the periphery of the shaft becomes, as it bears and revolves in the holes in the arms of the yoke, and thereby preventing the shaft from moving endwise.

The pinions are now fastened on to the ends of the shaft. The yoke, with the lever 6 and 7 attached, is so affixed to the perch, by means of small bolts permitting it to be slid a little back and forth on the level of the perch, that, using the upright handle, 7, as a lever, the horizontal bar 6 slides forward just enough to bring the pinions into proper depth on the graduated wheels. - To the very centre of the barrel 3, on the shaft 4, is also attached one end of a chain or rein of leather, cord, or other strong material, having a hook on the other end.

When it is desired to use the invention attached to a carriage, the horse-reins are first hooked to the chain or rein on the barrel 3, as appears in the diagram C, the shaft, by means of the lever-handle 7, is brought, with its end-pinions, into proper depth on the graduated wheels, and thus the moment the horse attempts a forward motion, the wheels set the shaft revolving, the check-rein is wound thereon, drawing back with it the horse-reins, and at the very instant he would start, the strain is brought to bear upon the reins with a force proportionate to the force and rapidity of his own movements.

When check is no longer needed, the lever-handle 7 reversed, throws the pinions on the shaft out of pitch-

ing, entirely clear of the graduated wheels, as they should ever be held when not required for use, and they cease to rotate.

The distance which the horizontal bar 6 must slide on the perch to bring the pinions into or throw them out of action and proper depth, is regulated by inserting in the bottom of the vehicle a small iron or any metallic plate, 8, having a slit and one ratchet-tooth, as represented. The upright lever 7 passes through the slit, and, when moved forward or backward, is retained in either place, in or out of pitching, by being made to rest on the cross-line of the tooth, or the line at its base, the length of one tooth being all-sufficient to bring the pinions into action, or throw them altogether out of action at any time, at the pleasure of the occupant.

I claim as my invention—

The combination and arrangement of the two gears 1 1, the two pinions 2 2, the shaft 4, the barrel 3, the yoke 5, and the slide 6, as applied to the two wheels and their axle, and as provided with a chain and hook, the whole being as and for the purpose specified.

MAURICE O'CONNELL.
